No. 37,010.

Patented June 28, 1904.

UNITED STATES PATENT OFFICE.

WILLIAM D. PAULSON AND RICHARD D. HEINBOCKEL, OF MANITOU, COLORADO.

DESIGN FOR A PAPER-WEIGHT.

SPECIFICATION forming part of Design No. 37,010, dated June 28, 1904.

Application filed December 11, 1903. Serial No. 184,835. Term of patent 3½ years.

To all whom it may concern:

Be it known that we, WILLIAM D. PAULSON and RICHARD D. HEINBOCKEL, citizens of the United States, and residents of Manitou, in the county of El Paso and State of Colorado, have invented a new, original, and ornamental Design for a Paper-Weight, reference being had to the accompanying drawing, in which the figure is a plan view of a paper-weight, showing our design.

We claim as new and desire to secure by Letters Patent—

The ornamental design for a paper-weight, herein shown.

WILLIAM D. PAULSON.
RICHARD D. HEINBOCKEL.
